Patented July 13, 1976

240,490

FLORAL HOLDER BASE

John Kevin Hunt, 10920 S. Rolmar,
Oak Lawn, Ill. 60453

Filed Feb. 24, 1975, Ser. No. 552,635

Term of patent 14 years

Int. Cl. D6—06

U.S. Cl. D6—196

FIG. 2.

FIG. 1.

FIG. 4.

FIG. 1 is a perspective view of a floral holder base showing my design;

FIG. 2 is a top plan view of the floral holder base shown in FIG. 1;

FIG. 3 is a side elevational view of the floral holder base shown in FIG. 1;

FIG. 4 is a bottom plan view of the floral holder base shown in FIG. 1.

The broken lines showing a post and container in FIG. 1 are for illustrative purposes only.

I claim:

The ornamental design for a floral holder base, as shown and described.
